CLAIM

We claim the ornamental design for a skateboard deck, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front perspective view of our skateboard deck;

FIG. 2 is a top, rear perspective view thereof;

FIG. 3 is a bottom, front perspective view thereof;

FIG. 4 is a bottom, rear perspective view thereof;

FIG. 5 is a top view thereof;

FIG. 6 is a bottom view thereof;

FIG. 7 is a left side view thereof;

FIG. 8 is a right side view thereof;

FIG. 9 is a front side view thereof; and,

FIG. 10 is a back side view of our skateboard deck.

The broken lines in the figures depict portions of the article that form no part of the claimed design.
